UNITED STATES PATENT OFFICE.

GRENVILLE HEMAN ROOD, OF SAN ANTONIO, TEXAS.

SPARK-ARRESTER.

SPECIFICATION forming part of Letters Patent No. 651,273, dated June 5, 1900.

Application filed August 30, 1897. Renewed November 11, 1899. Serial No. 736,688. (No model.)

To all whom it may concern:

Be it known that I, GRENVILLE HEMAN ROOD, a citizen of the United States, residing at San Antonio, in the county of Bexar and 5 State of Texas, have invented a new and useful Spark-Arrester, of which the following is a specification.

This invention relates to spark-arresters and draft-regulators for locomotive-boilers, 10 its object being to provide a simple and efficient mechanism of this character which will effectually prevent the escape of cinders and sparks through the smoke-stack without necessitating the use of woven-wire netting commonly employed for this purpose and by 15 means of which the draft may be regulated by the fireman or engineer from the cab of the locomotive.

With this object in view the invention consists of the several details of construction and combination of parts, as will be fully described hereinafter and particularly pointed out in 20 the claims.

In the drawings, Figure 1 is a vertical longitudinal sectional view of a portion of a locomotive-boiler equipped with my improved spark-arrester. Fig. 2 is a vertical transverse section on the line $x-x$ of Fig. 1. Fig. 3 is a detail perspective view of the pivoted 25 plate detached. Fig. 4 is a detached detail.

Similar reference-numerals indicate similar parts in the several figures.

1 indicates the boiler, 2 the flue-sheet, 3 the smoke-box, 4 the smoke-stack, and 5 the exhaust-nozzle, all of which may be of any ordinary or approved construction, except that the latter may, if desired, be of greater capacity than usual, as will be explained hereinafter.

40 6 indicates a plate which extends in a horizontal plane from the flue-sheet just above the top row of flues to nearly the front end of the smoke-box. The plate 6 extends entirely across the smoke-box and is secured to the 45 sides thereof and to the flue-sheet in any suitable manner.

7 indicates a curved plate bolted or otherwise secured to the front end of the plate 6 and extending upwardly and forwardly therefrom, and its ends fit close to the opposite sides of the smoke-box and may be secured thereto in any suitable manner, if preferred.

8 indicates a pivoted plate, the upper edge of which is curved, as indicated at 9, in order that it may fit closely against the upper portion of the smoke-box, while its lower edge is 55 preferably straight.

11 indicates a rod, to which the plate 8 is riveted or otherwise secured, and this rod is journaled in openings 12, formed in the sides 60 of the smoke-box at opposite points. The rod projects at one end beyond the outer face of the smoke - box and is provided with a crank-arm 13.

14 indicates a rod connected to the crank- 65 arm 13 and is designed to extend back to the cab of the engine, and it will preferably be provided with a handle 15 and also with notches (indicated by 16) adapted to engage in a suitable catch (indicated by 17) in order 70 to hold it in any adjusted position desired.

The plate 8 is so pivoted within the smoke- 75 box that when its upper curved edge is in engagement with the upper portion of the smoke-box the said plate will lie in a plane substantially parallel with the plane of the curved plate 7.

18 indicates an extension of the smoke- 80 stack projecting downwardly within the smoke-box, preferably to a point about midway between the horizontal plate 6 and the top of the smoke-box and directly over the exhaust - nozzle, which latter projects upwardly through an opening in the plate 6.

When the engine is running, the pivoted 85 plate 8 should always occupy the position indicated in full lines in Fig. 1, and the smoke, cinders, and products of combustion will pass from the flues along under the plate 6, up over the curved extension 7, down between said extension and the plate 8, and under the latter to the space in the smoke-box 90 above the horizontal plate 6, with which the stack communicates. During its passage in this manner the cinders and sparks will become separated from the lighter products of combustion, and the latter will be forced out through the stack by the exhaust-steam in the usual manner or will pass out naturally in the event the engine is not running. The 100 downward extension of the stack is a further preventive against the escape of sparks or cinders from the smoke - box through the smoke-stack, as will be clearly understood.

In getting up steam the plate 8 should be rocked on its pivot to the position indicated in dotted lines in Fig. 1, with its curved edge engaging the curved plate 7, when the products of combustion will be free to pass over the top of the curved plate 7 directly into the space in the smoke-box above the plate 6 and from thence out through the smoke-stack.

By the use of my invention and by reason 10 of its effectually preventing the escape of sparks and cinders out through the smoke-stack I am enabled to dispense entirely with the use of wire-netting, and thus obtain a freer draft, which allows the use of a larger 15 exhaust-nozzle, and thus prevents back pressure on the pistons, which results in a considerable saving of fuel.

It will be understood that changes in the form, proportion, and the minor details of 20 construction may be resorted to without departing from the spirit or sacrificing any of the advantages of this invention.

Having thus described the invention, what I claim is—

25 1. The combination with a locomotive smoke-box and the smoke-stack, of a horizontal plate supported within the smoke-box and engaging the flue-sheet above the flues and the sides of the smoke-box, and provided 30 at its front end with an upwardly and forwardly curved extension, and a plate pivoted within the smoke-box above the horizontal plate and to the rear of its curved extension and having its upper edge curved to fit the 35 smoke-box, and means to rock the pivoted plate, substantially as described and for the purpose specified.

2. The combination with a locomotive smoke-box, the smoke-stack, and the exhaust-nozzle, of a horizontal plate supported within the smoke-box and engaging the flue-sheet above the flues and the sides of the smoke-box, and provided at its front end with an upwardly and forwardly curved extension, said plate having also an opening for the passage of the end of the exhaust-nozzle, and a plate pivoted within the smoke-box above the horizontal plate and to the rear of its curved extension and having its upper edge curved to fit the smoke-box, and means to rock the pivoted plate, substantially as described. 45

3. The combination with a locomotive smoke-box, and the smoke-stack, of a horizontal plate supported within the smoke-box and engaging the flue-sheet above the flues and the sides of the smoke-box, and provided at its front end with an upwardly and forwardly curved extension, a plate pivoted within the smoke-box above the horizontal plate and to the rear of its curved extension, and having its upper edge curved to fit the smoke-box, means to rock the pivoted plate, an extension projecting downwardly from the smoke-stack within the smoke-box, and an exhaust-nozzle extending through the horizontal plate 60 immediately below said smoke-stack extension, substantially as described. 65

In testimony that I claim the foregoing as my own I have hereto affixed my signature in the presence of two witnesses.

GRENVILLE HEMAN ROOD.
